UNITED STATES PATENT OFFICE

HENRY THOMAS, OF LONDON, ENGLAND, ASSIGNOR TO U. S. SLICING MACHINE COMPANY, OF LA PORTE, INDIANA, A CORPORATION OF INDIANA

WORK-PIECE HOLDER FOR SLICING MACHINES

Application filed December 15, 1925, Serial No. 75,628, and in Great Britain December 22, 1924.

This invention relates in general to machines for slicing meat and other materials and has particular reference to work-piece holders for such machines (sometimes termed last slice holders) for gripping and supporting the material to be sliced.

Supports or holders of the character stated are known in which a number of rods or bars are turnably mounted in a vertical frame and have a plurality of lateral prongs capable of being projected forward, by turning the rods or bars, into engagement with the substance to be supported. Generally, the prongs are arranged to be projected forward into their operative positions through slots provided in a plate attached to the front of the frame, which plate constitutes a bearing surface against which the substance can be placed before the prongs are so projected and whilst they still occupy positions in rear of the front surface of the plate.

In accordance with the embodiment of the present invention which has been selected for the purpose of illustration, I provide a work-piece holder or last slice holder of such construction and arrangement that the bars themselves form a series of flat bearing surfaces all in the same plane when the prongs are inoperative, the said bearing surfaces serving in lieu of the usual front plate, which can therefore be dispensed with.

The construction and arrangement of said prong bars is also preferably such that they themselves form a series of flat bearing surfaces all in the same plane when the prongs are operative as well as when they are inoperative. To this end the prong bars may be of angular formation and so arranged that one side or flange of such bar is adapted to form part of a flat surface constituted by a plurality of said sides or flanges arranged all in the same plane when the prongs on said bars are inoperative and another side or flange of said bar is adapted to form part of a flat surface constituted by a plurality of such sides or flanges arranged all in the same plane when the prongs on said bars are operative.

In some cases, if so preferred, the prong bars may be shaped and arranged so as to

present, such, a flat surface simply when the prongs are operative.

Another feature of the invention consists in so mounting the prong bars and arranging the mechanism for operating the same that said parts can be easily and quickly dismounted for cleaning and other purposes, and also easily and quickly reassembled without requiring any special skill on the part of the operator. The preferred construction of the prong rods or bars makes it perfectly easy properly to reassemble them, an operation which hitherto required considerable skill.

The operating mechanism may be such as described and claimed in the specification of my co-pending patent application Serial No. 75,629, filed December 15, 1925, for Holders or supports for slicing machines. The operating mechanism is such that the prong-bars will all be turned simultaneously in the same direction and in that case the prongs will be arranged on the bars in such manner that they all project the same way, upwards or downwards in the operative position; or adjacent bars may be turned in opposite directions. In the latter case the prongs of adjacent bars will be arranged to project in opposite directions, as heretofore.

Two constructional embodiments of our invention are illustrated, by way of example, on the annexed drawings, whereon:—

Fig. 1 is an elevation of the back of one form of last slice holder;

Fig. 2 is a top plan view corresponding to Fig. 1;

Fig. 3 is a section on the line 1—1 in Fig. 1;

Fig. 4 is an elevation of the back of the other constructional embodiment referred to;

Fig. 5 is a top plan view, partly in section, corresponding to Fig. 4; and

Fig. 6 is a section on the line 6—6 in Fig. 4.

Referring first to Figs. 1 to 3:

The last slice holder therein illustrated comprises a frame having two side members 1 and 2 formed, respectively, with projecting claws 3 and 4 and 5 whereby the last slice holder can be attached to the substance support or table of a slicing machine in the usual manner. The frame also comprises a top

member 6 having a handle 7 and a number of prong-bars 8 are rotatably mounted in superposed relationship between the side members 1 and 2 of the device. Each prong-bar is of angular formation and one of the sides of the bar is formed, intermediate its ends, with a series of spaced pointed prongs 9 projecting from said side, and parallel thereto, forwards towards the front of the last slice holder, see particularly Fig. 3.

As shown on the drawings each prong bar is L shaped in section consequently presenting two sides or flanges at right angles; but, of course, the bars may be solid and shaped so as to present two flat sides.

Hereafter throughout the specification the reference to side or sides is to be understood as including flange or flanges in the case of L shaped or like bars.

The prongs on one prong bar are arranged out of alignment with those of the next adjacent bar, see Fig. 1 and recesses 10 are formed in all the vertical sides except that of the upper most bar so that when said prong-bars are rotated the prongs on one bar will not foul the side of the prong-bar immediately beneath while the clearance between two adjacent bars will be considerably reduced by this arrangement. A journal, or pin, 11 is formed at both ends of a prong-bar 8 and the bearings for the journals disposed in the side member 1 of the last slice holder frame are formed as circular apertures not open to the front or back wall of said side member. The bearings for the journals arranged in the side member 2, however, are slotted, and open out in the back of the member 2, as shown at 12 in Figs. 2 and 3, for a purpose to be referred to hereinafter.

A rack member 13, formed on one edge with rack teeth 14, is slidably arranged at the back of the side member 2 of the frame, being guided thereon by means of pins 15 and 16 screwed in to the member 2 and engaging in elongated slots 17 and 18 formed in the rack member. Toothed segments 19 are secured to the prong-bars 8, which latter are so spaced that the toothed segments do not mesh with each other. All the toothed segments are, however, in mesh with the teeth 14 on the rack member 13 and the latter is operated by a lever 20 pivoted to said member by a pin 21 and having an elongated slot 22 in which the pin 16 is engaged. The slot 22 is also formed with a portion 23 wherein the pin 16 engages when the lever 20 is in its normal position in which the prongs 9 are inoperative as indicated in Fig. 3.

In this position of the prongs the vertical sides of the prong-bars 8 constitute a series of flat bearing surfaces which together form a flat surface substantially equal in area to that of the usual slotted front plate which is used in last slice holders as previously constructed and which the present construction

and arrangement of the prong-bars 8 makes it possible to eliminate. If, now, the piece of substance to be sliced is held against the flat surface constituted by the vertical sides of the prong-bars and the lever 20 is depressed, the co-action of the slot 22 in said lever and the pin 16 will cause the rack member 13 to slide downwards and as the rack teeth 14 mesh with the toothed segments 19 the angular prong-bars will be rotated in unison and their movement be uni-directional, the prongs 9 being projected into said substance to hold the latter firmly while it is being sliced. It will be understood that a series of flat surfaces, against which the substance is held by the prongs, is thus constituted by the sides on which said prongs are formed, said sides being then all in the same vertical plane when the prongs project into the substance. It will be obvious therefore that owing to the angular formation of the bars a series of flat surfaces is presented both when the prongs are operative and inoperative. The arrangement of the slot 22 in the operating lever and the co-acting pin 16 is such that the prong-bars are at all times locked against movement in either direction except by means of the operating lever.

The slotted or open bearings 12 for the journals 11 of the prong-bars 8 make it possible to dismount said bars for cleaning or other purposes very rapidly, as it is only necessary to remove the two pins 15 and 16 and thereafter to remove the rack member 13, whereupon the journals 11 can be withdrawn from said bearings and the prong bars removed from the frame and readily replaced. By applying a straight edge to the vertical sides of the prong bars after the journals 11 are engaged in the bearings 12, said vertical sides can all be arranged in the same plane to form a flat surface before replacing the rack member 13 and the pins 15 and 16.

In the modified construction illustrated in Figs. 4 to 6 the arrangement is such that adjacent prong bars 8 are rotated in opposite directions, the prongs 9 on two adjacent bars being proximate in inoperative position, see Fig. 6. In order to cause two adjacent prong bars to rotate in opposite directions, two rack members 23 and 24 are employed and the toothed segment 19 on one prong bar; for instance, that on the topmost bar in Fig. 4 is arranged out of alignment with the toothed segment 19 on the next adjacent bar, so that two separate rows of toothed segments are thus formed. The inner rack member 23 is slidably arranged on the back of the side member 2 of the frame and is formed with elongated slots 25 and 26, the outer rack member 24 being slidably arranged on the back of the rack member 23 and the two rack members held against movement away from the side member 2 by means of pins 27 and 28 screwed into said side member and pass-

ing through the slots 25 and 26 in the inner rack-member and elongated slots 25^a and 26^a in the outer rack member. The rack member 23 is formed with a set of rack teeth 29 meshing with one of the two rows of toothed segments 19 and the rack member 24 is also formed with a set of rack teeth 30 meshing with the other row of toothed segments 19. The operating lever 20 is, in this case, pivoted by means of a pin 31 to the outer rack and is also formed with an elongated slot 22 engaged by the pin 28 whereby, when said lever is operated, the outer rack member is caused to move upwards or downwards as the case may be. The inner rack member would, however, remain stationary and in order to cause it to move simultaneously with the outer rack member a toothed pinion 32 is rotatably mounted on a pin 33 screwed into the side member 2 of the last slice holder frame, said pinion being accommodated in an elongated slot 34 in the inner rack member while the head of the pin 33 is arranged in an elongated recess 35 in the inside of the outer rack member. The inner rack member is provided with rack teeth 36 engaging one side of the pinion 32, the other side of the latter being engaged by teeth 37 formed on the outer rack member. Thus, as the outer rack member is moved upwards or downwards, as the case may be, the engagement of the pinion 32 with the two sets of teeth 36 and 37 causes the inner rack member 23 to move in the opposite direction to the rack member 24, the adjacent prong bars 8 and prongs 9 thereon also moving in opposite directions.

As in the constructional embodiment of the invention previously described, the bearings 12 for the journals 11 adjacent the side member 2 of the frame are slotted or open at one side so that the prong bars 8 can be readily removed for cleaning or other purposes and the arrangement of the slot 22 in the operating lever 20 and the pin 28 engaged therein is such as to lock the prong bars 8 firmly against movement at all times except by means of the operating lever.

The mechanisms described above for operating the prong bars 8 in unison are comprised in my invention described and claimed in the specification relating to my co-pending patent application Serial No. 75,629, filed December 15, 1925; my present invention being fully defined by the claims which follow hereafter. It will be obvious that I could vary the method of rotating the prong bars without departing from the present invention.

If so desired each prong bar may be shaped so as to present merely a flat side when the prongs are turned into the inoperative position, or, if desired, merely when turned into the operative position, this is not, however, so advantageous as shaping each bar

so as to present two flat sides, one when the prongs are in the inoperative position and one when the prongs are in the operative position.

Having now fully described my invention what I claim and desire to secure by Letters Patent is:—

1. In a work-piece holder for slicing machines, a plurality of work-piece engaging members respectively carrying impaling means and shiftable to move their impaling means into and out of engagement with the work-piece; said members collectively providing a flat arresting abutment against which the work-piece may be pressed prior to encountering the impaling means and while being impaled. 75

2. In a work-piece holder for slicing machines, a plurality of work-piece engaging members respectively carrying impaling means and shiftable to move their impaling means into and out of engagement with the work-piece; said members collectively providing a substantially flat arresting abutment against which the work-piece may be 90 pressed, said members having one set of flat surfaces which are presented to receive the work-piece before the work-piece encounters the impaling means, and another set of surfaces to move into work-piece receiving position simultaneously with the presentation of the impaling means to the work-piece. 95

3. In a work-piece holder for slicing machines, a frame, a plurality of combined abutment and impaling member removably mounted in said frame, said members each comprising a bar having abutment surfaces disposed at an angle to one another and said impaling means comprising prongs projecting from one of the abutment surfaces on 105 each bar.

4. In a work-piece holder for slicing machines, a frame, a plurality of combined abutment and impaling members removably mounted in said frame, said members comprising a vertical series of bars mounted to rotate in said frame, each bar having abutment surfaces disposed at an angle to one another, means for collectively rotating the bars to present different ones of said abutment surfaces to the work-piece and said impaling means comprising prongs projecting from one of the abutment surfaces on each bar. 110

5. In a work-piece holder for slicing machines, a frame, a plurality of combined abutment and impaling members removably mounted in said frame, said members each comprising an L-shaped bar having an abutment surface on each of its two sides, said impaling means comprising prongs projecting from one of the sides of the bars, and means for selectively presenting either of the abutment surfaces on each bar to the work-piece. 120

6. In a work-piece holder for slicing ma- 130

chines, a frame, a plurality of combined abutment and impaling members removably mounted in said frame, said members each comprising an L-shaped bar having an abutment surface on each of its two sides, said impaling means comprising prongs projecting from one of the sides of the bars, and means for selectively presenting either of the abutment surfaces on each bar to the work-piece and with all of the abutment surface thus presented disposed in the same vertical plane.

7. In a work-piece holder for slicing machines, a plurality of members carrying impaling elements, means for moving said members to position said elements into and out of operative or work-piece engaging position, said members each presenting a continuous abutment surface throughout the length thereof and disposed toward the work-piece when said members are moved into one of said positions, said abutment surfaces collectively forming an abutment surface for the work-piece, the area of each of said abutment surfaces presented by each of said members toward the work-piece being determined by the length and breadth of said members.

8. In a work-piece holder for slicing machines, a plurality of members carrying impaling elements, means for moving said members to position said elements into and out of operative or work-piece engaging position, said members each presenting a continuous abutment surface extending substantially the length of the work-piece holder and disposed toward the work-piece when said members are moved into one of said positions, said abutment surfaces collectively forming an abutment surface for the work-piece, the area of each of said abutment surfaces presented by each of said members toward the work-piece being determined by the length and breadth of said members.

9. In a work-piece holder for slicing machines, a plurality of work-piece engaging members movable into and out of work-piece engaging position, said members when moved into one of said positions collectively providing a flat abutment surface for the work-piece.

10. In a work-piece holder for slicing machines, a plurality of work-piece engaging members movable into and out of engagement with the work-piece, said members when moved into one of said positions presenting a series of substantially flat continuous abutment surfaces extending substantially the length of the work-piece holder and disposed toward the work-piece, said surfaces collectively forming an abutment surface for the work-piece.

11. In a work-piece holder for slicing machines, a plurality of work-piece engaging members movable into and out of work-piece

engaging position, said members when moved into one of said positions presenting a series of flat abutment surfaces.

12. In a work-piece holder for slicing machines, a plurality of work-piece engaging members movable into and out of engagement with the work-piece, said members presenting a series of substantially flat abutment surfaces when moved into engagement with the work-piece.

13. In a work-piece holder for slicing machines, a plurality of work-piece engaging members movable into and out of engagement with the work-piece, said members presenting a series of abutment surfaces which collectively provide a substantially flat abutment surface for the work-piece when said members are moved into engagement with the work-piece.

14. In a work-piece holder for slicing machines, a plurality of work-piece engaging members movable into and out of engagement with the work-piece, said members presenting a series of substantially flat abutment surfaces positioned in the same plane when moved into engagement with the work-piece.

15. In a work-piece holder for slicing machines, a plurality of members carrying impaling elements, means for moving said members to position said elements into and out of operative or work-piece engaging position, said members presenting a series of continuous abutment surfaces extending substantially the length of the work piece holder and disposed in a plane toward the work-piece when said members are moved to position said elements in operative position.

16. In a work-piece holder for slicing machines, a plurality of work-piece engaging members respectively carrying impaling means and shiftable to move their impaling means into and out of engagement with the work-piece, said members collectively providing a substantially flat arresting abutment against which the work-piece may be pressed, said members having one set of flat surfaces which are presented to receive the work-piece before the work-piece encounters the impaling means, and another set of flat surfaces to move into work-piece receiving position simultaneously with the presentation of the impaling means to the work-piece.

17. In a work-piece holder for slicing machines, a plurality of work-piece engaging members respectively carrying impaling means and shiftable to move their impaling means into and out of engagement with the work-piece, each of said members presenting a continuous substantially flat abutment against which the work-piece may be pressed prior to encountering the impaling means.

18. In a work-piece holder for slicing machines, a plurality of work-piece engaging members respectively carrying impaling means and shiftable to move their impaling

means into and out of engagement with the work-piece, each of said members having two continuous substantially flat faces, said faces on each member collectively forming an abutment surface for the work-piece when said impaling means are moved into engagement with the work-piece and when said means is moved out of engagement with the work-piece.

19. A work-piece holder for slicing machines, a frame, a plurality of combined abutment and impaling members rotatably mounted in said frame, said members comprising a vertical series of bars each having two sides disposed substantially at right angles to each other, prongs attached to one of the sides of said bars, said prongs being spaced from and disposed substantially parallel with said last mentioned sides, said last mentioned sides being disposed in parallel horizontal planes, and said other sides being disposed in the same vertical plane when said prongs are in inoperative position, and means to rotate said bars to position the sides having the prongs in the same vertical plane.

In testimony whereof I affix my signature.
HENRY THOMAS.
